UNITED STATES PATENT OFFICE.

CHARLES E. COLEGROVE, OF EAST CLEVELAND, OHIO, ASSIGNOR TO WHITE SEWING MACHINE COMPANY, OF CLEVELAND, OHIO, A CORPORATION OF OHIO.

ELECTRICALLY-DRIVEN DROPHEAD SEWING MACHINE.

Application filed July 11, 1921. Serial No. 483,698.

To all whom it may concern:

Be it known that I, CHARLES E. COLEGROVE, a citizen of the United States, residing at East Cleveland, in the county of Cuyahoga and State of Ohio, have invented a certain new and useful Improvement in Electrically-Driven Drophead Sewing Machines, of which the following is a full, clear, and exact description.

10 This invention relates to electrically driven drop head sewing machines.

More particularly, the invention relates to the control of the motor, i. e., to the mechanism for starting and stopping it, 15 and for controlling its speed, and the chief objects of the invention are to avoid the necessity for long conductors between the motor and the rheostat through which the motor is controlled, and to provide a construction which permits the use of substantially a fixed wiring between the rheostat and motor.

Further, the invention aims to provide a construction wherein both the motor and 25 rheostat are carried by the swinging platform to which the sewing machine head is attached, and to provide in connection therewith rheostat operating means so constructed and arranged with reference to the rheostat.

30 stat that the sewing machine head can be lowered into the cabinet or elevated to operative position very readily with reference to the rheostat controlling parts carried by the fixed part of the cabinet without causing 35 any mechanical damage to the rheostat controlling parts and without requiring the manual connecting or disconnecting of any of the parts to effect this movement. Still further, the invention aims to mount the

40 rheostat in such a manner on the swinging platform carrying the head, and to provide a rheostat operating device or mechanism which is not only efficient and satisfactory in a mechanical sense, but one of such a

45 nature that when the head is lowered into the cabinet the rheostat arm is automatically removed from the parts normally controlling it, and when the head is elevated the rheostat arm is automatically restored to 50 operative position with respect to the controlling mechanism.

The invention may be briefly summarized as consisting in certain novel combinations and arrangements of parts and details of 55 construction which will be described in the

specification and set forth in the appended claims.

In the accompanying sheets of drawings, Fig. 1 is a vertical sectional view of the cabinet and swinging platform carrying the head, motor and rheostat; Fig. 2 is a vertical sectional view in section at right angles to the section of Fig. 1, showing the head swung or folded into the interior of the cabinet; Fig. 3 is a top plan view of a 60 sewing machine with the head elevated to operative position; Fig. 4 is a detailed sectional view through the platform showing the rear side of the rheostat; Fig. 5 is a 65 detailed sectional view showing particularly 70 the bell crank which is mounted on the rear inner side of the cabinet, this bell crank forming a part of the rheostat operating mechanism and being designed to shift the rheostat arm, the section being taken substantially along the line 5—5 of Fig. 2, 75 looking in the direction indicated by the arrows; Fig. 6 is a view similar to Fig. 2, but showing the head elevated to operative 80 position; and Fig. 7 is a horizontal sectional view substantially along the line 7—7 of Fig. 6, looking in the direction indicated by the arrows.

Referring now to the drawings, 10 represents a conventional type of cabinet for sewing machines of the drop head type, this cabinet being supported on legs 11. At the top of the cabinet is a swinging platform 12 which in this instance is hinged to swing about the horizontal axis 13 near the upper 90 front part of the cabinet.

If desired, this platform may be connected by a wire cable or equivalent means to a hinged extension leaf 14 designed to be swung over the top of the cabinet when 95 the platform is lowered into the same, as for example, in the manner illustrated in Patent No. 1,338,834, granted May 4, 1920, to Theo. Kundtz, for cable guide for drop head sewing machine cabinets, and Patent 100 No. 1,379,828, granted May 31, 1921, to Theo. Kundtz, for drop head sewing machine cabinet. However, the details of the cabinet are not material to the present invention, and the platform 12 may be otherwise pivotally mounted and operated in any 105 suitable manner.

On the platform 12 is mounted a sewing machine head 15 which may be of usual construction. The machine is adapted to 110

- be driven by an electric motor which may be mounted on the head or platform in any desired manner, but in this instance the motor, which is indicated at 16, is mounted 5 on a bracket 17 secured to the upright portion 18 of the arm of the head, the motor having a driving wheel 19 adapted to be held in frictional driving engagement with the hand wheel 20.
- 10 Before taking up the parts more directly involving my invention, it might be mentioned that the motors of modern electrically driven sewing machines of the drop head type are controlled by cutting resistance into and out of the motor circuit, the resistance being arranged in the form of a rheostat of some suitable type, involving a swinging switch or rheostat arm.
- In all prior constructions of which I am 20 aware the rheostat is mounted on a fixed part of the cabinet, in which event the motor carried by the swinging head or platform moves relative to the rheostat, thus requiring the use of long flexible conductors to 25 permit this relative movement. To avoid the use of these flexible conductors which are objectionable and unsafe from an electrical standpoint, I provide my invention, which in its broad aspect comprises the 30 mounting of the rheostat in the platform so as to swing with the motor.
- In the embodiment of the invention illustrated the rheostat is shown at 21, and as will be observed, the rheostat is mounted on 35 the under side of the swinging platform 12 near what is in effect the lower edge of the platform when the platform is in its lower position, or the rear edge adjacent the rear wall of the cabinet when the platform is in 40 elevated position.
- Inasmuch as the motor and rheostat are in relatively fixed position the motor can be connected to the rheostat by relatively short and substantially firm conductors, indicated 45 at 22. The lower ends of the conductors are connected to a plug 23 adapted to fit into a socket suitably wired to the rheostat so that the rheostat and motor can be readily disconnected should it be desired for any reason 50 to remove the motor from the machine. Alongside the socket which receives the plug 23 is a second socket 24 which is adapted to receive a plug connected to a suitable source of current, the location of these two sockets 55 being indicated in Fig. 3.
- Though the details of the rheostat are immaterial to the present invention, preferably it involves, as is usually the case, a swinging arm 25 indicated in Fig. 4, and in this 60 instance the arm is provided with an operating lip or projection 25^a projecting from the rear side of the rheostat case, and therefore projecting close to the rear wall 10^a of the cabinet when the platform is elevated.
- 65 The rheostat may be controlled by the foot or knee of the operator, but in this instance the left side of the cabinet is provided on the inner side with a knee lever 26, shown in Figs. 1 and 2. This lever which is pivoted between its ends onto a bracket 27 on the inner side of the cabinet so that it may rock horizontally, extends from a point near the front of the cabinet to a point near the rear wall 10^a, as clearly shown in Fig. 2. To the inner or rear upstanding end of the lever is connected a rod 28 which extends alongside or across the rear wall 10^a of the cabinet, in a diagonal direction, as most clearly shown in Fig. 1.
- The upper outer end of this rod is connected to a bell crank 29 pivoted to a bracket 30 on the inner side of the rear wall near the corner of the cabinet diagonally opposite from the lower lever 26. This bell crank which is located at the rear of the rheostat when the swinging platform is elevated is provided with a forwardly projecting lip 31 which is adapted to engage and shift the rearwardly projecting lip 25^a of the rheostat arm.
- A spring 32 connected to the bell crank and to the bracket 30 as shown in Fig. 5 restores the bell crank and other parts of the mechanism to normal position when pressure is relieved from the front end of the lever 26, and the rheostat arm is automatically restored to off position by a spring, not shown, but forming a part of the rheostat, when the bell crank 29 is moved to normal or off position by the release of knee lever 26.
- It is to be understood that there is no fixed connection between the bell crank 29 and rheostat arm, but these two parts have projecting portions which overlap, one portion projecting rearwardly and the other projecting forwardly, and the bell crank and rheostat arm swinging about substantially coincident centers so that when the bell crank is swung to the right, as viewed in Figs. 1 and 5, it will engage and swing to the right the rheostat arm so as to start and gradually cut resistance out of the motor circuit to cause the motor to come up to maximum speed, and when the bell crank is swung in the reverse direction the rheostat arm swings in the same direction, cutting resistance into the motor circuit so as to reduce its speed and opening the motor circuit so as to stop the motor when the arm reaches its normal off position.
- When the head is elevated to the position shown in Fig. 1, the operator by the pressure of the knee on the forward end of lever 26 rocks the lever and this motion is transmitted by the rod 28 to the bell crank 29 so as to swing it about its pivot, and thus operate the rheostat as just explained, the lever 26 being automatically returned to normal position by the spring 32 when the pressure on the lever is relieved. Thus the motor

can be started and stopped and operated at any speed within the limits provided by the design of the rheostat and motor.

When the operator desires to lower the head into the cabinet this can be very readily done, for the construction is such that the rheostat arm simply swings away from the bell crank 29, as is obvious from an inspection of Fig. 1, and as the rheostat and motor are in fixed relation there is no flexing of the conductors 22 connecting the motor to the rheostat, and as the platform and head swing downward there is no disarrangement of or injury to the rheostat operating mechanism. Furthermore, as the rheostat swings downward with the platform 12 the rheostat arm is automatically returned to off position, and the control of the rheostat is automatically interrupted so that should the operator lower or start to lower the head while the driving motor is in operation the motor is automatically stopped.

Likewise, when the platform is swung up to operative position at the top of the cabinet, the rearwardly projecting portion of the rheostat arm is automatically restored into the path of the forwardly projecting part of the bell crank 29, so that the control of the motor through the knee lever 26 is immediately restored.

Obviously, many of the details of the parts may be modified, and I therefore do not desire to be confined to the precise arrangements or constructions shown, but aim in my claims to cover all modifications which do not involve a departure from the spirit and scope of my invention.

Having described my invention I claim:—

1. In an electrically driven sewing machine of the drop head type, a cabinet comprising a relatively fixed part and a movable part carrying the head of the sewing machine, a motor for operating the machine, a rheostat for controlling the motor both the motor and rheostat being movable with the head when swung to and from operative position, and rheostat controlling means separate from and unattached to said rheostat and carried by the fixed part, said rheostat controlling means having a member engageable with a part of the rheostat only when the head is in the operative position.
  2. In an electrically driven sewing machine of the drop head type, a cabinet having a fixed portion and a movable portion, a sewing machine head mounted on the movable portion and adapted to be swung down into the cabinet or upward into operative position, a motor for driving the machine and a rheo-
- stat for controlling the motor both movable with the head and with said movable part of the cabinet, and means on the relatively fixed part of the cabinet adjacent the rheostat when the head is in operative position for operating the rheostat, said rheostat having a part with which said operating means is adapted to engage when the head is in operative position.
3. In an electrically driven sewing machine of the drop head type, a cabinet having at the top a swinging platform, a sewing machine head mounted on the platform, a driving motor above the platform a rheostat in fixed relation with respect to the motor and mounted on the under side of the platform, and a rheostat controlling means having a member mounted on a fixed part beneath and adjacent the platform of the cabinet and positioned alongside the rheostat when the head is in the operative position, said member being engageable with the rheostat to operate the same only when the head is in the operative position.
4. In an electrically driven sewing machine of the drop head type, a cabinet having at the top thereof a platform adapted to be swung from operative horizontal position to a position within the cabinet, a head carried by the platform, a motor for operating the machine, a rheostat for controlling the motor mounted upon the under side of the platform, a rheostat controlling means carried by the fixed part of the cabinet and including an operating part toward and from which the rheostat is moved when the platform is elevated to operative position and lowered respectively, said rheostat having a part with which said operating means is adapted to engage when the head is in operative position.
5. In an electrically driven sewing machine of the drop head type, a cabinet having a fixed portion and a movable platform, a head mounted on the platform, a motor above the platform for operating the machine, a rheostat for controlling the motor mounted on the lower side of the platform so as to swing therewith, a rheostat controlling means mounted on the fixed part of the cabinet and comprising a portion adjacent the rheostat when the platform and head are in their upper position, the rheostat being moved toward and from said portion of the rheostat operating means when the platform and head are elevated and lowered respectively.

In testimony, I hereunto affix my signature.

CHARLES E. COLEGROVE,
